US00D632671S

(12) **United States Design Patent**
Wada

(10) **Patent No.:** **US D632,671 S**
(45) **Date of Patent:** **** Feb. 15, 2011**

(54) **SPEAKER**

(75) Inventor: **Takayuki Wada**, Tokyo (JP)

(73) Assignee: **Sony Corporation**, Tokyo (JP)

(**) Term: **14 Years**

(21) Appl. No.: **29/347,522**

(22) Filed: **Feb. 19, 2010**

(51) LOC (9) Cl. **14-01**

(52) U.S. Cl. **D14/216**

(58) **Field of Classification Search** D14/204, D14/210–216, 172; 181/143–144, 147–148, 181/150–153, 157–159, 198–199; 381/300–303, 381/306, 332–333, 336, 345, 361–364, 386–388

See application file for complete search history.

(57) **CLAIM**

The ornamental design for a speaker, as shown and described.

DESCRIPTION

FIG. 1 is a perspective view of a speaker showing my new design; and,

FIG. 2 is a front elevational view thereof.

Portions in broken lines are for illustrative purpose only and form no part of the claimed design. The dot-dash broken lines define boundaries of, and are not included in the claimed design.

1 Claim, 2 Drawing Sheets

FIG.1

FIG.2
